US00D876818S

(12) **United States Design Patent** (10) Patent No.: **US D876,818 S**
 Lieberman et al. (45) Date of Patent: ** Mar. 3, 2020

(54) **CASE FOR A VIBRATING ELECTROMECHANICAL DEVICE FOR FEMALE STIMULATION**

(71) Applicant: **Mating Components, LLC**, Brooklyn, NY (US)

(72) Inventors: **Janet Lieberman**, Brooklyn, NY (US); **Alexandra Fine**, Brooklyn, NY (US); **David Block**, Brooklyn, NY (US); **Amanda Couto**, Pembroke Pines, FL (US); **Tiffany Wyche**, Brooklyn, NY (US)

(**) Term: **15 Years**

(21) Appl. No.: **29/619,930**

(22) Filed: **Oct. 3, 2017**

(51) LOC (12) Cl. **03-01**
 (52) U.S. Cl. .... **USPC D3/203.1**

(57) **CLAIM**

The ornamental design for a case for a vibrating electromechanical device for female stimulation, as shown and described.

DESCRIPTION

FIG. 1 is a top, left and front perspective view of a case for a vibrating electromechanical device for female stimulation showing our new design;

FIG. 2 is a back elevational view thereof;

FIG. 3 is a front elevational view thereof;

FIG. 4 is a top plan view thereof;

FIG. 5 is a bottom plan view thereof; and,

FIG. 6 is an exploded top and front perspective view thereof. The broken lines depict portions of the article that form no part of the claimed design.

1 Claim, 5 Drawing Sheets
